ATTORNEY

UNITED STATES PATENT OFFICE.

MILTON T. ROSENHEIM, OF PHILADELPHIA, PENNSYLVANIA.

LUMINOUS SWITCH-KEY.

1,077,305.

Specification of Letters Patent.

Patented Nov. 4, 1913.

Application filed March 20, 1913. Serial No. 755,593.

To all whom it may concern:

Be it known that I, MILTON T. ROSENHEIM, a citizen of the United States, and a resident of the city of Philadelphia, county 5 of Philadelphia, and State of Pennsylvania, have invented certain new and useful Improvements in Luminous Switch-Keys, of which the following is a specification, reference being had to the accompanying drawing.

The principal objects of my invention are, to provide a luminous switch key for use in turning on or off electric switches or the controlling cocks of gas fixtures and the 15 like, or for use in push switches or push buttons, of such construction that it may be visible from any position in a dark room; to provide a luminous switch key which shall permanently retain its luminosity under all 20 conditions; which shall not require exposure to daylight or to artificial light from time to time, in order to maintain it in a luminous condition, and to provide a luminous switch key, which may be cheaply and easily constructed, and which may be used in connection with the ordinary type of gas or electric fixtures or switches now upon the market.

Other objects and features of my invention 30 will appear in the following specification and the drawing forming a part of this application.

In the drawing, Figure 1 is a side elevation of a luminous switch key constructed in 35 accordance with my invention; Fig. 2 is an end view thereof taken on line 2—2 in Fig. 1, the key being removed from its shaft, and Fig. 3 is a vertical transverse section of the same taken on the line 3—3 in Fig. 1. Fig. 4 40 is a side elevation of a slightly modified form of luminous switch key embodying the features of my invention; Fig. 5 is an end view of the same; Fig. 6 is a vertical transverse section taken on the line 6—6 in Fig. 45 4; Fig. 7 is an elevation of one of the luminous switch keys, the subject of this invention, in connection with an electric light socket and bulb, and Fig. 8 is an elevation of a gas controlling cock operated by a 50 similar key showing portions of the gas pipe on either side of the cock.

Referring to the drawings, one embodiment of my invention shown in Figs. 1, 2 and 3, consists in a key having a body portion 1, which may be formed of any desired transparent or translucent material, such as

glass, and which is preferably constructed by cementing or otherwise fastening together two or more sections 2, 3, by means of a thin layer of cement 5, or in any other desired manner. These sections, which may be formed in any desired shape, are preferably hollowed out on their meeting faces in such manner as to form a cavity of any desired depth in the said faces, so that when 60 the sections 2, 3, are brought together and fixedly secured to each other by the cement 5 or other means to form the body of the key, a closed cavity 6 of any desired size and depth, within the limits afforded by the 65 key, is formed therein, as clearly shown in Figs. 2 and 3.

For the purpose of attaching the key to the switch or other object, the key may be provided at one end, which may be suitably 70 enlarged for this purpose, with a cylindrical threaded aperture 7 of any required depth, the threads of which, if desired, may be molded in the glass or other material of which the key is made, or may be cut there- 75 in in any desired manner for the purpose of receiving the threaded end of the switch shaft 10, as clearly shown in Fig. 1, or if desired, the key may be attached to the switch shaft 10 in any other suitable manner. In 80 case the key be formed with an aperture 7, in the manner described, it is generally preferable to make this aperture of such depth that it will not connect with the cavity 6 which is formed within the body of the key, 85 as shown in Fig. 2, although, if desired, it may be made of such depth as to connect with said cavity.

Within the cavity 6, which is formed preferably in the manner heretofore described, 90 and preferably before the two sections of the key are cemented or otherwise secured together, is introduced a luminous substance 12 in any desired quantity, which substance may preferably consist of radiumized zinc 95 sulfid, or some other radiumized substance or compound. This substance may be placed within the cavity in solid, liquid, pasty or powdered form, as clearly shown in Fig. 3, 100 or if desired, it may be applied as a coating to the walls of the cavity in a manner to be hereinafter described. This substance, owing to its inherent capacity for giving off light, will, as may be readily seen, serve to illuminate the key, and owing to the fact 105 that the luminous material is surrounded on all sides by the translucent or transparent

substance composing the body portion of the key, the latter will appear as a luminous body from any position which the observer may assume within the room in which it is 5 situated.

In Figs. 4, 5 and 6, is shown a slightly modified form of key embodying the principles of my invention. This key is also constructed with a body portion 13 comprising two sections 14, 15, hollowed out on their meeting faces to form a suitable cavity 17 in a manner similar to that already described. For the purpose of holding the sections in fixed relation to form the key 10 body in this type of key, a plurality of rivets 18 may be employed, which pass through suitable apertures in the sections 14, 15, and serve to secure the same firmly together. For affixing the key to the switch 15 shaft, or other object, a threaded stub shaft 20 is secured within a suitable cavity at 20 one side of the key body, which may be suitably enlarged at that point, by cementing it therein or in any other suitable manner, and projects outwardly from the key, 25 as clearly shown in Fig. 4, being operative to engage in a suitably threaded socket in the switch shaft or other like object, to which it may be desired to secure the key. 30 In Fig. 6, the luminous substance within the cavity 17 is shown as being applied to the sides thereof as a coating 22 rather than as filling the cavity in the form of a paste or powder, or otherwise, as shown in Fig. 35 3. Of course, it will be evident that, if desired, such a coating may be used in a key of the form shown in Fig. 1, or the cavity 17 in the form of the key shown in Fig. 4 may be filled with a luminous substance 40 rather than coated therewith, if it be found desirable.

Figs. 7 and 8 respectively clearly illustrate the use of a luminous key constructed in accordance with the principles of my invention, in connection with an electric light socket, and with a gas controlling cock on a gas pipe or fixture. In fact, keys embodying the principles of my invention may be used in any place or for any purpose in a manner similar to the ordinary type of keys now in general use, while possessing moreover the great advantage of being continuously luminous at all times, as well as the further advantage that such a key will always 45 present a luminous appearance, no matter from what angle it may be observed.

While I do not desire to limit myself to the use of radiumized zinc sulfid, or other radiumized substance, in a key constructed 50 in accordance with the principles of my in-

vention, as, if I desire, I may make use of any other luminous substance within the cavity in the body of the key, yet I have found that radiumized zinc sulfid, or other radiumized substances, possess a distinct advantage in that they do not have to be exposed from time to time to daylight, or other light, in order to keep them in a luminous condition, and hence, a switch key embodying such a substance will retain these luminous qualities practically indefinitely although it may be located where it is never exposed to light of any sort, as in a dark closet or cellar. 65 70

Having thus fully described my invention, I claim and desire to protect by Letters Patent of the United States:

1. A luminous switch key, comprising a translucent body portion having an interior cavity and containing a mass of luminous substance, the luminosity of said substance being visible from any angle, and means for attaching said key to a switch or the like. 80

2. A luminous switch key, comprising a translucent body portion having a plurality of sections, the meeting faces of said sections being hollowed out to form a cavity within said body portion, means for securing said sections in fixed relation, 90 means for attaching said key to a switch or the like, and a mass of luminous substance within said cavity, the luminosity of said substance being observable from any angle. 85

3. A luminous switch key, comprising two translucent members having the centers of their meeting faces hollowed out and the edges of said faces united by an adhesive, means for attaching said key to a switch or the like, and a mass of luminous substance 95 within the cavity between said members; the luminosity of said substance being visible from any angle. 100

4. A luminous switch key, comprising two translucent members having portions 105 of their meeting faces hollowed out and forming a closed cavity, means for holding said members in permanent contact, means for attaching said key to a switch or the like, and a mass of comminuted luminous 110 material within said cavity, said material being visible from any angle.

In witness whereof, I have hereunto set my hand and seal, this 13th day of March A. D. 1913.

MILTON T. ROSENHEIM. [L. S.]
